DESIGN FOR A CASE FOR COIN CHANGING MECHANISM

Helen Dunn, Aurora, Ill., assignor to C. Earl
Hovey, Kansas City, Mo., as trustee

Application December 26, 1944, Serial No. 117,094

Term of patent 14 years

(Cl. D52—3)

To all whom it may concern:

Be it known that I, Helen Dunn, a citizen of the United States, residing at Aurora, in the county of Kane and State of Illinois, have invented a new, original, and ornamental Design for a Case for Coin Changing Mechanism, of which the following is a specification, reference being had to the accompanying drawing, forming a part thereof.

Fig. 1 is a front elevational view of the case for coin changing mechanism, showing my new design.

Fig. 2 is an edge view thereof; and
Fig. 3 is a top plan view thereof.

I claim:
The ornamental design for a case for coin changing mechanism, as shown.

HELEN DUNN.
